UNITED STATES PATENT OFFICE.

DAVID E. HUNTER, OF CAMBRIDGE, MASSACHUSETTS, ASSIGNOR TO THE LIBRARY BUREAU, OF BOSTON, MASSACHUSETTS.

DRAWER FOR CARD-INDEXES.

SPECIFICATION forming part of Letters Patent No. 657,415, dated September 4, 1900.

Application filed January 27, 1900. Serial No. 2,940. (No model.)

To all whom it may concern:

Be it known that I, DAVID E. HUNTER, a citizen of the United States, residing at Cambridge, county of Middlesex, State of Massachusetts, have invented an Improvement in Drawers for Card-Indexes, of which the following description, in connection with the accompanying drawings, is a specification, like letters on the drawings representing like parts.

My invention relates to improvements in drawers or holders for cards and similar articles, and applies more particularly to the follower-block and its connections with the drawer.

Various devices have been provided heretofore for maintaining the cards in more or less compact relation, and the more common of these devices has been a block extending across the width of the box and movable lengthwise thereof, said block having a sloping rear wall at the side adjacent the cards in order that the latter may rest in reclined position adapted for inspection. My present invention contemplates a follower-block having a locking member pivotally mounted on the back side thereof and slotted or recessed at its lower end to engage a bar or plate held rigidly in the drawer and capable of being swung into and out of biting engagement with said bar or plate.

Various other details of construction will be more particularly pointed out in the following description of my invention, and the operation thereof will be set forth therein, and the invention will be more particularly defined in the appended claims.

In the drawings, Figure 1 is a transverse vertical section of a typical drawer provided with my invention, the follower proper being shown in rear elevation and a portion thereof broken away for clearness of understanding. Fig. 2 is a central longitudinal section taken on the irregular line 2 2, Fig. 1. Figs. 3 and 4 are top plan views of the plates used in my invention.

The box *a* may be of any kind common or desired for the purpose of holding card-indexes, records, or any form of cards, papers, &c., which it is usual to stand on edge in regular order in a box or drawer.

Along the bottom of the box, preferably along the middle thereof, I provide a depression herein shown and preferably extending in two parallel portions *a'*, and on the raised intermediate part *a*² I secure a bar or plate *a*³, said bar being shown in Figs. 3 and 4 in top plan and in Fig. 1 in transverse section. Viewing the latter figure, it will be seen that the edges of this bar or plate *a*³ project over the depressions *a'*, so as to form guides or tracks on which the follower-block *a*⁴ may slide.

Secured by suitable means, as by screws *a*⁵, to the under side of the follower-block is a plate *a*⁶, having lips or ears *a*⁷, stamped out, preferably, at its edges, as clearly shown in Fig. 3, and bent downwardly and preferably in L shape to embrace the guides constituted by the edges of the plate *a*³. The latter is cut away at *a*⁸ in order to permit the follower and its lugs *a*⁷ to be properly mounted in sliding engagement with the plate *a*³.

In Fig. 3 I have shown four openings *a*⁸ cut out of the plate *a*³, and in Fig. 4 I have shown only two of these openings, these figures also showing said openings cut only slightly larger than the lugs *a*⁷ for the reception of the latter, although it will be understood that I am not limited to the size of the openings nor to the number, it being only necessary to provide suitable means for the ready placing of the lugs *a*⁷ beneath the guides of the plate *a*³. In Fig. 4 I have shown two of the lugs of the plate *a*⁶ as formed within the body of the plate *a*⁶, as indicated at *a*⁹, this being a neat arrangement, especially for wide blocks. Preferably, also, the plate *a*⁶ is cut out at *a*¹⁰, herein shown as a circular aperture, and the follower-block is recessed at *a*¹² immediately above said opening *a*¹⁰ for the reception of a spring *a*¹³, said spring giving more or less frictional retarding effect and serving also to prevent the tendency of the block to tip up under the weight of the supported cards in case the lug *a*⁷ should become bent or should fit too loosely. At its rear side I provide a fulcrum *a*¹⁴, herein shown as formed by recessing the back of the block obliquely at *a*¹⁵, both above and below the fulcrum-point *a*¹⁴, and in this recess I mount a clamping device *a*¹⁶, which pivots on said fulcrum-point.

and is retained in any suitable manner, as by a staple a^{17} . Said clamping device a^{16} is provided with a slot a^{18} , herein shown as extending obliquely to the length of said clamping device or member, although it will be understood that I am not limited to the direction of the slot or recess a^{18} nor otherwise to the specific details herein mentioned.

10 In a recess a^{19} and preferably adjacent the upper end of the member or lever a^{16} I mount a spring a^{20} , bearing against the rear side of said lever a^{16} and constituting means for maintaining said clamping device normally in biting engagement with the track or bar a^8 .

15 The form of block herein shown has its lower front edge cut away at a^{21} in order to prevent the creeping up thereon of the cards; but I do not herein claim said improvement, as it is already claimed in connection with 20 another application.

The manner of employing my invention is as follows: The plate or bar a^8 is first screwed or otherwise secured in the bottom of a box or drawer, either at one side thereof or down 25 the middle, said drawer having suitable provision for raising the edges of said bar or plate, so that they may be engaged as required, said relatively-raised position being either secured by providing depressions along the 30 edges thereof or in any other way, so that a substantially T-shaped track may be had, and then the follower-block, constructed as before explained, is placed in position over the apertures a^8 , so that the lugs a^7 or the 35 forward pair thereof will drop into openings a^8 , and then the block is slid forward, it being understood that the back pair of lugs a^7 are similarly entered through the openings a^8 , these openings preferably being arranged 40 adjacent the front end of the box. As the follower-block is moved back into operative position in the box it will be understood that it cannot possibly become dislodged from the plate a^8 in any manner whatever, and also by reason of the constant frictional engagement therewith of the retarding-spring a^{19} it does not tend to tip up, and all rattling is positively prevented. As the block 45 is stopped in any position it will be automatically gripped or locked positively in place by the biting or gripping action of the jaws or recessed part a^{18} of the clamping device a^{16} , said automatic action being due to the spring or other actuating device a^{20} . If 50 the operator desires to shift said block either forwardly or rearwardly in the box, he simply pinches inwardly on the lever a^{16} , thereby bringing the inclined slot a^{18} more or less into parallelism with the adjacent edge of the plate a^8 , so that the block can be readily slid along 55 said plate.

One principal object of my present invention is to provide an exceedingly-inexpensive construction, inasmuch as the commercial necessities which have been developed in this class of devices make it imperative that the expense of manufacture should be re-

duced to a minimum, and accordingly I believe that invention must be concentrated at the present time more upon simplifying and 70 cheapening the construction than upon the operation of the parts.

It will be observed that all the parts of my invention can be stamped or cut out practically from the raw material into the finished 75 shape by one blow, and none of the parts require any machining or manual manipulation aside from their stamping out, the result being that the element of labor is substantially eliminated, and the device is not 80 only greatly simplified in its parts, but is exceedingly inexpensive.

Having described my invention, what I claim, and desire to secure by Letters Patent, 85 is—

1. The combination with a receptacle for cards, of a plate constituting guides and secured to said receptacle, a follower-block having lips engaging said guides and maintaining the follower on said plate while permitting longitudinal movement, said plate having openings or notches cut in its edge to permit said lips to be inserted or removed. 90

2. The combination with a receptacle for cards, of a plate constituting guides and secured to said receptacle, a follower-block having lips engaging said guides and maintaining the follower on said plate while permitting longitudinal movement, said plate having openings or notches cut in its edge to 100 permit said lips to be inserted or removed, a cavity in the bottom of said block, and a spring or resilient member occupying said cavity and bearing in frictional engagement against said plate. 105

3. In a device of the kind described, a follower-block having a wide base, a track therefor, means holding said block on said track, and a spring carried by said block and engaging said track immediately beneath the 110 base of said block for steadyng and retardng said block on the track.

4. A card-receptacle, a follower-block movable longitudinally thereof, a bar or plate mounted in said receptacle, and a clamping 115 device for said block, said clamping device comprising a member pivotally mounted on the block and having a recess or jaws embracing said bar or plate and movable into and out of biting engagement therewith. 120

5. A card-receptacle, a follower-block movable longitudinally thereof, a bar or plate mounted in said receptacle, and a clamping device for said block, said clamping device comprising a member pivotally mounted on 125 the block and having a recess or jaws embracing said bar or plate and movable into and out of biting engagement therewith, and means automatically maintaining said pivoted member in biting position. 130

6. A card-receptacle, a follower-block movable longitudinally thereof, a bar or plate mounted in said receptacle, and a clamping device for said block, said clamping device

comprising a member pivotally mounted on the block and having a recess or jaws embracing said bar or plate and movable into and out of biting engagement therewith, and 5 a spring mounted in said block and bearing against said member for maintaining the same normally in one position.

7. A card-receptacle, a follower-block therein, a bar or plate mounted in said receptacle, 10 a fulcrum on the back side of said block, a clamping-lever mounted on said fulcrum, said clamping-lever having a recess or transverse slot for engaging said bar or plate, and being capable of turning on said fulcrum into 15 and out of locking engagement with said bar or plate.

8. A card-receptacle, a follower-block therein, a bar or plate mounted in said receptacle, a fulcrum on the back side of said block, a 20 clamping-lever mounted on said fulcrum, said clamping-lever having a recess or transverse slot for engaging said bar or plate, a

recess behind the upper end of said lever, and a spring therein bearing on said lever, movement of said lever toward said block 25 serving to disengage the lever from biting engagement with said bar or plate.

9. In a card-receptacle, a follower-block, locking means carried by said block for engaging a fixed portion of said receptacle, and 30 locking the block in desired adjustment, said locking means being movable toward and from said block, movement thereof toward said block serving to unlock the latter, and automatic means for moving the same away 35 from said block.

In testimony whereof I have signed my name to this specification in the presence of two subscribing witnesses.

DAVID E. HUNTER.
